UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed September 5, 1918, Serial No. 252,769. Renewed November 16, 1922.

To all whom it may concern:

Be it known that I, ERASTUS E. WINKLEY, a citizen of the United States, residing at Lynn in the county of Essex and State of Massachusetts, have invented certain new and useful Improvements in Heel-Building Machines; and I do hereby declare the following to be a full, clear, and exact description of the invention, such as will enable others skilled in the art to which it appertains to make and use the same.

This invention relates to an automatic heel-building machine, and it has special reference to a machine of this general class that is particularly adapted to build both decked leather heels and sections of heels that are composed of thin lifts and skivings of varying thicknesses and qualities.

It is common practice in the art to manufacture low heels that comprise leather lifts throughout, and also heels comprising a section of leatherboard lifts and a section of leather lifts. Such leather heels and heel-sections are frequently made up of a plurality of thin lifts and skivings of different thicknesses and qualities. In order to economize material and accommodate the pitch of the heel, it is customary to form such a heel in decks or levers of graded sizes, and it is sometimes desirable to form even the leather sections themselves in decks.

The leather sections may be either built up preliminarily into the form of a unitary section that may be suitably secured to the leather-board section of the heel, or, the leather section may be built into the heel at the same time and in the same manner that the leatherboard lifts are assembled.

In the manufacture of either all leather heels or leather sections of heels of this type, whether the sections are built into independent units before being attached to the leatherboard section or are assembled with leather-board lifts into a complete heel, the character or quality of the lifts is usually specified. For instance, the specification may call for a heel having 7/8ths of leather, 2/8ths being of grain leather, 2/8ths of "flexibles", and the remainder of skivings. Moreover, different sizes of leather lifts may be specified in order to produce a decked heel.

One of the objects of the present invention is to provide an automatic heel building machine for assembling successively in superposed relation, a sufficient number of lifts of varying or unknown thicknesses to form a heel or heel section of predetermined height.

Accordingly, a feature of the invention resides in the combination with means for holding a supply of lifts of varying or unknown thicknesses, of automatic mechanism operating upon a sufficient number of lifts, one at a time, to form a heel of definite height, for successively removing the lifts from the supply and depositing them one upon the other to build a heel of predetermined height. In order to definitely determine when a sufficient number of lifts have been assembled, it is convenient to employ a measuring mechanism which preferably functions after the deposit of each lift and thereby determines the progressive heights of the heel during its assembly. The component lifts of a heel, so built, are secured together by suitable means, and if desired, means dependent upon the height of the heel may be employed for effecting its ejection when fully built.

Another object of this invention is to provide a simple, compact and reliable machine for automatically building leather heels or leather heel-sections of the above-indicated character, the machine being constructed and arranged so that it may conveniently be adapted to segregate and to handle lifts of various qualities, as well as lifts of graded sizes.

More specifically, an object of the invention is to provide an automatic machine which shall be adapted to build a heel or heel-section of definite characteristics and dimensions, by successively transferring thin lifts of a certain quality or size and of varying thicknesses from one magazine and assembling them in a pile in superposed relation to a predetermined height of deck, then successively superposing upon the first deck, lifts of a different quality or size from another magazine until a prescribed height is attained, and then, if desired, similarly and progressively assembling another deck or other decks to build a completed heel.

or heel-section of the desired total height after which the completed product may be ejected and the cycle of operation repeated to build another like heel or heel-section.

5 In accordance with the preferred embodiment of the invention, the above mentioned objects are accomplished by means of a machine which embodies a plurality of magazines for containing and segregating lifts 70 of different qualities or sizes, from which lifts are removed one at a time and assembled in a pile in superposed relation by means of a picker that preferably is adapted to rotate continuously through successive 75 complete revolutions. An automatic measuring device is preliminarily set in accordance with the dimensions and characteristics of the heel or heel-section to be built and functions during the operation of the 80 machine to progressively measure the height of the pile or section as it is built, to selectively determine the magazine from which the lifts shall be taken, and finally to effect the actuation of a suitable ejecting device for discharging the completed product.

Other objects of the invention, and features of construction and operation by which they are obtained, will be readily apparent to those skilled in the art from the 85 following description of the illustrated embodiment of the invention. The invention, in its broader aspects, is not confined to the specific structural details and mode of operation set forth, and the advantages and 90 benefits thereof may be attained by machines differing widely in certain respects from that shown and described; therefore, only such limitations should be imposed as are indicated in the appended claims.

95 Throughout the specification and claims, the terms "heel" and "heel-pile" are used generically to include heel-sections, and the terms "lifts" and "heel-lifts" are employed in an inclusive sense, as defining any blank or layer of material capable of being handled by instrumentalities of the character described, more particularly such blanks as are useful in the formation of heels or heel-piles, from which heels are ultimately 100 produced and irrespective of the particular dimensions and shape of the blank or of the nature of the material of which it is composed.

105 The preferred embodiment of the invention is illustrated in the accompanying drawings, as building an all-leather decked heel, although it will be understood that the machine may be employed for building leather heel-sections, or for other analogous 110 purposes.

115 In the drawings Figure 1 is a view, in side elevation, of a machine constructed in accordance with the invention, the nearest side frame being removed for the sake of clearness; Fig. 2 is a view, partially in section

120 and partially in elevation, of the machine shown in Fig. 1, the section being taken on the line 2—2 of Fig. 1, and looking from left to right; Fig. 3 is a plan view of the machine shown in Figs. 1 and 2; Fig. 4 is 125 a view in cross section of a decked heel such as built by the machine; Fig. 5 is a perspective view of a mutilated lift or skiving, such as may be handled by the picker; Fig. 6 is a sectional plan view, on an enlarged 130 scale, of the machine, with certain parts removed to show the construction of the multi-path cam for determining the operation of the picker, the picker being shown in its depositing position; Fig. 7 is a view, similar to Fig. 6, of a portion of the machine, illustrating particularly the picker in position over the first magazine and the paste applying device in the act of applying paste to one of the deposited lifts; Fig. 8 is an enlarged sectional plan view showing the construction of the mechanisms for releasing the magazine clamps; Fig. 9 is a view similar to Figs. 6 and 7, showing particularly the picker in the act of actuating the 135 ejecting device; Fig. 10 is a detailed enlarged plan view of the toothed cam segment of the measuring device, the multi-path cam being shown in dotted lines with the gates or switches in position for causing the picker to act upon the lifts in the second magazine; Fig. 11 is an enlarged detail view, partially in section, of one of the gates and adjustable pins constituting a 140 part of the multi-path cam for selectively determining the magazine from which lifts are to be removed; Fig. 12 is an enlarged plan view, partially in section, of the machine, with certain parts removed to show particularly the construction of the measuring device and the automatic stops for the 145 paste applying device; Fig. 13 is an enlarged view, partially in section and partially in elevation, of a portion of the machine, the section being taken along the line 13—13 of Fig. 6, and showing particularly the operating mechanism of the measuring device; Fig. 14 is an enlarged front elevation of a portion of the machine, showing the picker in its depositing position; Fig. 15 is an enlarged view, partially in section and partially in side elevation, of the upper portion of the machine, the section being taken on the line 15—15 of Fig. 6 and showing particularly the measuring device and the construction and operating mechanism of the picker and the magazines; Fig. 16 is a perspective view, on an enlarged scale, of one of the magazines and its operating mechanism; Fig. 17 is an enlarged view of the cam and associated operating mechanism for effecting the actuation of the magazine clamps; Fig. 18 is an enlarged view, in elevation, of the cam and associated mechanism for actuating the 155 re-

reciprocating head and oscillating the toothed cam segment of the measuring device; Fig. 19 is an enlarged view, partially in section and partially in elevation, of the cam and associated mechanism for actuating the measuring device; Fig. 20 is an enlarged sectional view of a portion of the picker and reciprocating head, by means of which the picker is depressed to pick up and deposit a lift; Fig. 21 is an enlarged view, partially in section, of the paste applying device and the mechanism for immersing it in the paste-pot; Fig. 22 is an enlarged view of the cam and associated mechanism for actuating the stripper or measuring fingers; Fig. 23 is a sectional plan view, on an enlarged scale, of a portion of the picker; Fig. 24 is an enlarged plan view of an attachment which may conveniently be added to the machine and which embodies a finger for clamping or holding down the heel-pile while the stripper fingers are withdrawn, certain parts of the machine being illustrated in dotted lines; Fig. 25 is a view, in front elevation, of the attachment shown in Fig. 24; Fig. 26 is a view in side elevation of the attachment shown in Figs. 24 and 25; and Fig. 27 is an enlarged detailed view of the cam device for determining the operation of the clamping or positioning finger.

Referring to the drawings, the machine shown comprises, in general, a frame 30 for supporting the various component elements embodied in the machine; a plurality of magazines 32 for containing stacks of thin lifts or skivings L of varying thicknesses and qualities and of graded sizes; a picker 34 adapted to periodically rotate through complete revolutions and to successively transfer a plurality of lifts from the several magazines in turn and deposit them in superposed relation in the form of a heel-pile; a multi-path gate cam 36 including a plurality of adjustable gates or switches 40, 42, 44 and 46 for prescribing the path of movement of the picker and shifting its operation from one magazine to another in accordance with predetermined conditions; a reciprocating head 48 for depressing the picker to cause it to remove lifts from the respective magazines and to discharge or deposit them in a pile at an assembling station; a measuring device including a plurality of combined measuring and stripper fingers 50, a vertically movable and horizontally oscillatory toothed cam segment 52 and a plurality of adjustable pins 54, all serving in conjunction to periodically measure the height of the heel-pile as it is progressively built, and to automatically control the actuation of the gates or switches of the gate cam 36 to prescribe the operation of the picker in accordance therewith; a paste-applying device 56 for applying paste

to the upper surface of each of the lifts after it has been deposited at the assembling station; a plurality of stops 58 and 60 for respectively preventing the paste-applying device from applying paste to the support 70 or table upon which the heels are built and to the final lift of the pile; an ejector 62 for ejecting or discharging the heel when completed, and a clamping or positioning finger 64 for engaging each of the uppermost lifts of the heel as it is built and holding the lifts in position while the stripper fingers are laterally withdrawn.

Referring particularly to Figs. 1, 2 and 3, the frame 30, upon which the component parts of the machine are mounted, comprises side pedestal members 66 and 68 which are rigidly connected by means of a lower cross-beam 70, a lower supporting plate 72, an upper cross-beam 73 and an upper plate or assembling table 74. The rear portion of the plate 72 is substantially semi-circular in form and is adapted to support the magazines 32 and said plate is provided with a forwardly projecting arm 75 for supporting certain driving gears of the machine. The plate 74 serves as a table, on the front portion 77 of which the heels are assembled, and the respective ends thereof are provided with integral vertically projecting sleeves 76 which serve as guides or bearings for a plurality of vertical rods 78 upon the upper ends of which the reciprocating head 48 is mounted and by means of which said head is actuated.

The side pedestals 66 and 68 carry in suitable bearings a main power shaft 80, a cam shaft 82 and a crank shaft 84. The main power shaft 80 is provided with a fast pulley 86 and a loose pulley 88 with which a belt 90 driven from any suitable source of energy is adapted to cooperate. The belt 90 may be shifted from one pulley to the other at the will of the operator by means of a belt-shifter 92 of any suitable type that is provided with a handle 94.

The power shaft 80 is provided with a pinion 96 that meshes with a gear 98 that is mounted upon the cam shaft 82, through the agency of which the cam shaft is continuously rotated when power is supplied to the machine. The cam shaft is provided with a plurality of cams 100, 102, 104, 106, 108 and 110, by means of which the various component mechanisms of the machine are actuated in proper time cooperation, as will hereinafter be fully set forth. The various operating levers and bell cranks that cooperate with the several cams of the machine for actuating the component mechanisms thereof are mounted upon the crank shaft 84.

The assembling table 74 and the plate 72 are provided with suitable bearings for a central vertical shaft 112, which is rotated

continuously and effects the actuation of the picker. The lower end of the shaft 112 is provided with a gear 114 (Figs. 1 and 12) that is connected by means of an idler gear 116 to a gear 118 which is associated with a bevel gear 120, all of which are suitably journaled in the projecting arm 75 of the plate 74. The bevel gear 120 meshes with a cooperating bevel gear 122 that is fixed to the continuously driven cam shaft 82.

Having described the general construction of the supporting frame of the machine, together with the manner of mounting certain of the most important shafts thereof, consideration will be given to the various devices and mechanisms which go to make up the machine as a whole.

Referring particularly to Figs. 1, 6, 8, 12, 15 and 16, and with special attention to Figs. 1, 6 and 16, the several magazines 32 are of like construction and are mounted in a circular row upon the semi-circular rear portion of the plate 72, the row being concentric about the central shaft 112. In order to build a heel to the specifications hereinbefore assumed, the first magazine contains thin lifts of grain leather, the second magazine holds a stack of "flexibles" of a larger size, and the third a stack of skivings of a still larger size.

Each magazine comprises a V-shaped upright member 126, which projects upwardly to the full height of the magazine and which serves to position the rear or curved portions of the lifts contained therein. The lower end of the V-shaped member 126 is provided with a laterally extending base 128 having a plurality of elongated slots 130, through which suitable clamping devices 132 project for adjustably clamping the V-shaped member in position upon the plate 72. The base member 128 is also provided with a central slot or recess 134 in order to allow the free passage of a follower rod 136. Acting in conjunction with the V-shaped magazine member 126 is a shorter channel shaped member 140 which is provided with a base 142 that is suitably secured to the supporting plate 72. Pivoted to the upper end of this shorter magazine member 140, by means of a pin 143, is a movable clamping member 144 that constitutes an extension of the member 140 and, together with it, serves to position the breast edges of the stack of lifts contained within the magazine. The upper and inner surface of the clamping member 144 is provided with a plurality of teeth 146 which are normally brought into clamping engagement with the breast edges of the uppermost lifts in the magazine by means of a compression spring 148 that surrounds a rod 150 which is suitably positioned between a lug 152 of the clamping member

144 and a lug 154 that is secured to the magazine member 140.

The lifts within the magazines are supported upon follower plates 156 which are carried by the follower rods 136 that are movable vertically through suitable openings in the plate 72. The lower ends of the follower rods 136 of the respective magazines are provided with angularly shaped guides 160 (Fig. 12) that are secured thereto at their apexes, and the ends of which engage and slide upon a plurality of stationary guide-rods 162 that are positioned in suitable bearings upon the plate 72 and a bracket 164 constituting a part of the lower cross-brace 70. In order to independently and constantly urge the stack of lifts in each magazine in an upward direction, a flexible cord 166 is attached to the lower end of each follower rod 136, and said cord passes over pulleys 168 suitably mounted beneath the plate 72 and is attached to a weight 170. The constant tendency of the weight 170 to raise the follower and the stack of lifts supported thereon is normally opposed by the action of the spring-pressed magazine clamp 144, as has been already described.

During the operation of the machine, as the picker 34 functions to remove the uppermost lift from any of the magazines, it becomes necessary to effect the release of the magazine clamp 144 of the particular magazine upon which the picker acts, and this function is accomplished by means of the following apparatus, illustrated best in Figs. 6, 8, 15, 16 and 17. Upon the semi-circular plate 72 and adjacent the side of each magazine 32 is located an upwardly projecting bracket 174 (Figs. 8 and 16), to the upper end of which a bell-crank 176 is pivotally mounted upon a pin 178. The bell-crank comprises a substantially vertical arm 180 and a substantially horizontal arm 182 that carries at its end a roll 184. The upper end of the vertical arm 180 is provided with a pawl 186 which is pivotally mounted upon a pin 188, and the outer end of said pawl is provided with a shoulder 190 for the purpose of engaging a projecting lug 192 that is integral with the clamping member 144, to effect the release of the lifts in the magazine upon which the picker acts. The pawl 186 is provided with a lug 194, through which a bolt or pin 196 projects, said pin also projecting through a lug 198 that is formed integrally with the upper end of the arm 180. A coil spring 200 surrounds the bolt 196, and its upper end engages the under side of the lug 198 while its lower end engages an adjustable nut 202 that is threaded upon the bolt 196. With this construction, the spring 200 normally maintains the shoultered end of the pawl 186 in its elevated

position (Fig. 15) in which the engagement of the shoulder 190 with the lug 192 of the magazine clamp is prevented.

The several pawls 186, normally maintained in their elevated positions, as just described, are periodically actuated back and forth during the cycle of operation of the machine, by reason of the fact that the rolls 184 at the ends of the respective horizontal arms 182 of the bell-cranks cooperatively engage flanges 204 and 206 of a spool 208 (Fig. 17) that is loosely slidable upon the central shaft 112. A periodic sliding movement of the spool 208 is effected by means of a bell-crank 210 that is rotatably mounted upon the crank-shaft 84, one arm thereof being provided with a roll 212 that is located between the flanges 206 and 214 of the slidable spool 208, and the other arm being provided with a roll 216 that cooperatively engages a cam-path in the face of the cam 102. This cam 102 is provided with as many depressions 218 as there are magazines, so that during each cycle of operation of the machine, when the picker is in operative position above the respective magazines, the cam 102, through the agency of the mechanisms just described, actuates the clamp-releasing pawls 186 in their elevated positions through their idle paths of movement. The several pawls 186, therefore, are respectively adapted to release the clamps of the respective magazines, but for the fact that they are maintained in elevated positions by the springs 200.

In order to render operative the clamp-releasing pawl 186 of the particular magazine with which the picker 34 is cooperating, said picker is provided with an adjustable set screw 220 (Fig. 16) which engages the upper cam surface 222 of the adjacent pawl 186 when the picker is depressed into position just above the uppermost lift in the magazine. The engagement referred to effects the depression of that particular pawl 186 until the shoulder 190 thereof is brought into such position that it engages the lug 192 of the clamp member 144 when the pawl is projected inwardly by the operation of the cam 102, in the manner already described. Having effected the engagement just referred to, the inward stroke of the pawl actuates the clamp member 144 in opposition to the action of the spring 148 and thereby temporarily releases the lifts within the magazine, as will be understood. The stack of lifts in the magazine is therewith raised until the uppermost lift engages the picker which occupies its lowered position in which it acts as a stop to prevent the lifts from being forced upwardly out of the magazine.

As already stated, a plurality of lifts are successively removed from the several mag-

azines in turn and transferred to a position above the forward portion 77 of the table 74 and there deposited in a pile in superposed relation by means of a picker which is actuated through successive complete revolutions, during each of which a lift is transferred and deposited. The picker 34 is of the so-called paste-picker type, such as set forth and claimed generically in a co-pending application, Serial No. 208,443, filed December 22, 1917, by the present applicant.

Referring particularly to Figs. 6, 13, 15 and 16, the picker 34 comprises a plate 226 of the general configuration of a dinked heel-life which is provided with oppositely disposed side notches or slots 228 to accommodate the measuring or stripper fingers 50 during the lift-depositing operation. The plate 226 is secured to the lower end of a rod 230 which is slidably mounted upon a supporting arm 232 by means of upper and lower bearings 234 and 236. A collar 238 is pinned to the rod 230 just below the upper bearing 234, and between this collar and the lower bearing 236 a coil spring 240 surrounds the rod and acts to normally maintain the rod and associated picker-plate 226 in their elevated position. In this position, the upper end of the rod 230 projects above the upper bearings 234 and into a position in which it may be engaged by a portion of the reciprocating head 48 during its operation, whereby said picker may be depressed, for a purpose and in a manner to be herein-after set forth. The collar 238, as shown particularly in Fig. 23 is provided with a plane rear surface 242 (Fig. 23) for engagement with the outer surface 244 of the picker arm 232, thus preventing any rotative movements of the picker.

The picker arm 232 is provided with a sleeve 246 which loosely surrounds the central shaft 112 and which rests upon a hub 248 of a crank-arm 250 that is pinned to the shaft 112 above the plate or table 74. A collar 252 is pinned to the upper end of the shaft above the picker arm 232. The free end of the crank-arm 250 is pivotally connected to a link or arm 254 by means of a bolt 256, and said arm is provided with a laterally extending member 258, having at its end a boss 260 for the purpose of actuating the ejector 62, as will be hereinafter described. The outer end of the link or arm 254 carries a pin 262, the upper and lower ends of which are provided with rolls 264 and 266 respectively. The upper roll 264 projects into and cooperatively engages the sides of a cam slot 268 that is provided in the lower surface of an enlarged portion 270 of the main picker arm 232, as shown particularly in Figs. 6 and 15. The lower roll 266 cooperates with the gate-cam 36.

The combined cooperation of the cam-slot 268 and the gate-cam 36 upon the link or

5 arm 254, which carries the upper and lower rolls 264 and 266, prescribes the path of movement and operation of the periodically rotating picker, as will be more fully set forth. In general, it will be understood from the foregoing description, that as the central shaft 112 and associated crank arm 250 are continuously rotated, the picker arm 232 and picker 34 are accordingly drawn through successive complete revolutions. The timing or speed of actuation of the picker during different portions of its travel, however, depends upon the cooperative action of the cam-slot 268 and the gate-cam 36, upon the rolls 264 and 266, just referred to, and to be hereinafter more fully explained.

20 As already mentioned, the picker 34 is of the paste-picker type; that is, its under surface is adapted to be periodically coated with paste or any suitable adhesive, so that as the stack of lifts in any magazine are temporarily released and raised, the uppermost lift in the magazine is brought into 25 engagement with the picker plate 226 in its lowered position and caused to adhere thereto and may consequently be removed and transferred as desired. This form of picker is particularly adapted for use in the present machine, which is designed primarily to handle thin lifts and skivings, for the reason that with this type of construction a single lift may be transferred irrespective of the degree of its thinness; in 30 fact, lifts which are so defective as to have relatively large central openings therein, such as shown in Fig. 5, may be successfully handled. Moreover, this form of picker is capable of handling, without injury and 35 without deformation, thin lifts which are likely to be mutilated and badly crumpled when handled by a picker of the claw type.

40 In order to effectively coat the picker during each revolution and before its operation to remove a lift from any of the magazines, a paste-pot 274 is mounted upon the table 74 and is provided with a rotatable cylinder or roll 276 which is partially immersed in the paste with which the paste-pot 45 is filled. As the picker-plate 226 moves over the paste roll 276, it functions to coat the lower surface of the plate with paste, as will be understood.

50 In accordance with the present invention, the machine is adapted to automatically build decked heels, such as illustrated in Fig. 4, of a plurality of thin lifts and skivings which are initially placed in graded qualities and sizes in the several magazines 55 and which are transferred therefrom successively and deposited in the form of a heel-pile, in superposed relation, at each revolution of the picker. The picker first acts upon lifts of grain leather in the first magazine, 60 and after a sufficient number of lifts have

been transferred therefrom and assembled, the operation of the picker is shifted to the second magazine, upon which it successively acts until the "flexibles" have been assembled to the required height of the second deck of 70 the heel, after which the operation is shifted to the third magazine, upon which it functions in a similar manner until the third deck is built up of skivings and the heel finally completed, whereupon the ejector is 75 thrown into operation and the completed heel kicked out or discharged from the machine. For best operation, it is necessary that the picker pause temporarily over the respective magazines in order to give sufficient time for the removal of the lifts therefrom, while a similar pause is desirable at the depositing or assembling station to provide an interval during which the transferred lift may be placed upon the pile and 80 discharged from the picker.

85 This shifting of the operation of the picker from one magazine to the next, and the provision of pauses or periods of rest in the rotative movement of the picker to enable lifts to be withdrawn from the magazines and then deposited in a pile, is accomplished through the agency of the multi-path gate-cam 36, the construction and operation of which will now be set forth.

90 The gate-cam 36 (Figs. 2, 6, 10 and 15) is substantially heart-shaped in configuration and is fixed to the elevated portion of the table 74 in such position as to surround the central shaft 112. As shown most clearly 95 in Fig. 10, the gate-cam 36 is provided with a plurality of paths in which the lower roll 266 of the picker operating mechanism is adapted to travel. One path 280 extends around the periphery of the cam and is provided opposite the assembling station with a straight portion 282, which is disposed at a slight angle to a line radiating from the central shaft 112. The angularity of the straight portion 282 to the radius is similar 100 to that of the cam-slot 268 in the lower surface of the picker arm 232, so that when the picker arm occupies the position shown in Fig. 6, in which the picker is adapted to deposit a lift upon the pile being built, the cam-slot 268 of the picker arm coincides with the straight portion 282 of the peripheral cam path 280 of the gate-cam 36. By 105 reason of this registration of the cam-slot and cam path, in which the respective rolls 264 and 266 travel, there is no tendency to move the picker arm 232 and the picker while said rolls are traversing the full length of these straight cam path portions. Hence, 110 although the central shaft 112 rotates continuously, the peculiar construction of the gate-cam 36, acting in conjunction with the slotted picker arm 232, permits said picker arm and picker to pause temporarily during 115 the period required for the rolls to trav-

erse the length of the respective cam paths under consideration. An interval of rest, therefore, is provided for the picker and its position over the assembling station, during 5 which period the deposition of the lifts is accomplished.

Adjacent the several magazines, and disposed at the same angularity as the cam-slot 268 in the picker arm 232 and the straight 10 portion 282 of the peripheral cam path 280, the gate-cam 36 is provided with a plurality of inwardly extending cam paths 284, 286, and 288, all of which communicate in common with an inner curved cam path 290, 15 which is extended through a cam-path 292 to communicate with the peripheral cam path 280 in the region of the assembling station. The utilization of the cam paths 284, 286 and 288 is controlled by the operation 20 of the respective pivotally mounted gates or switches, 40, 42 and 44.

These gates or switches are of like construction and therefore only the gate or switch 40 will be described. This gate 40 is 25 of bell-crank form, and is pivoted upon a pin 294 and provided with an arm 296 which forms one side of the angularly disposed cam path 284 adjacent the magazine when the gate or switch occupies its closed position, as 30 shown in Fig. 9. The other arm 298 of the bell-crank gate 40 serves, in the open position, as shown in Fig. 6, to deflect the cam-roll 266 from the peripheral cam path 280 into the cam path 284, and in the closed position, shown in Fig. 9, constitutes a side 35 of the peripheral cam path 280, and therefore prevents the cam-roll 266 from entering the cam path 284.

If the gate or switch 40 adjacent the first magazine occupies its open position, as shown in Fig. 6, the cam-roll 266 is deflected in the straight cam portion 284 which, by reason of its coincident angularity with the cam-slot 268 in the picker arm 232, causes the movement of the picker to 45 be arrested temporarily over the first magazine while a lift is being removed therefrom, in a manner similar to that explained in connection with the temporary pause of 50 the picker over the lift depositing position.

As the roll 266 enters the cam path 284, it engages the arm 296 of the gate 40 and effects its counter-clockwise rotation into 55 the closed position shown in Fig. 9, after which the cam-roll 266 continues to travel the inner cam path 290 and communicating cam path 292, until it again reaches the position shown in Fig. 6, during which 60 operation, after the temporary pause above referred to, the picker is rotated to its lift depositing position.

After the gates or switches have been 65 closed by the travel of the cam-roll 266, in the manner just described, they remain

in that position unless and until they are restored to open position by means of the measuring apparatus, which acts upon the adjustable pins 54 (Fig. 11) with which each arm 296 of the gates or switches is 70 provided and which project downwardly through suitable curved slots 302 in the bottom of the gate-cam 36, as will be hereinafter fully described.

From the foregoing description, it will 75 be understood that if the gate or switch 40 adjacent the first magazine be open, the picker is arrested in position to operate upon the lifts in said magazine, after which the picker transfers the lift and deposits 80 it at the assembling station, while if the gate 40 be closed, the picker passes by the first magazine and its operation is shifted to one of the other magazines, dependent upon the positions of the gates or switches 85 42 and 44 adjacent thereto. In Fig. 6, the gate or switch 40 is open, which therefore determines the operation of the picker upon the first magazine. In Fig. 10, the gate 40 adjacent the first magazine being 90 closed and the gate 42 adjacent the second magazine being open, the operation of the picker is shifted to the second magazine. In a similar manner, if the gates 40 and 42 of the first and second magazines 95 be closed and the gate 44 of the third magazine be open, the operation of the picker upon the third magazine is prescribed. In the event that all of the gates or switches 40, 42 and 44 are closed, as shown in Fig. 9, the cam-roll 266 travels the peripheral cam 280, and therefore the picker passes by all of the magazines without operation thereon and is brought to the position shown, in which the ejecting 100 device 62 is actuated to eject the heel-pile which has just been built, as will be herein-after fully set forth.

Unlike the gates or switches 40, 42 and 44 that are located adjacent the respective 105 magazines, the gate 46 merely constitutes a single arm which is pivoted upon a pin 306 and is adapted to be actuated by the cam-roll 266 to its respective positions, according as said cam-roll traverses the communicating cam-path 292 or the peripheral cam path 280, as will be understood.

When the picker occupies its position over any of the magazines, it is necessary to make provision for depressing the picker 110 into its stop position immediately above the magazine where the uppermost lift may be raised into engagement with and adhere to the picker-plate 226 that is coated with paste. It is also necessary to provide means for depressing the picker in its depositing position to place the transferred lift upon the heel-pile and to effect its discharge. These functions are accomplished by means 115 of the reciprocating head 48, the construc- 120

tion and operation of which will now be set forth.

Referring particularly to Figs. 1, 2, 3, 15, 18, and 20, the head 48 is carried upon 5 the upper ends of the rods 78 and is secured thereto by nuts 310. The rods 78 are slidably mounted in the sleeves 76 which constitute integral parts of the plate or table 74, and the lower end of each 10 rod has a spool 312 (Fig. 18) pinned thereto. An arm 314 is bifurcated at its outer end and provided with rolls 316 which are positioned between the flanges of one of the spools 312. Said arm 314 is keyed 15 to the left hand end of the crank shaft 84, as viewed in Fig. 2. The other end of the crank-shaft 84 is provided with a bell-crank 318 (Figs. 1 and 2), one bifurcated arm 320 of which corresponds to 20 the arm 314 at the other end of the shaft and carries similar rolls 316 which engage a like spool 312 that is secured to the lower end of the other rod 78. The other arm of the bell-crank 318 carries a roll 324 that 25 cooperatively engages a cam-path 326 in the face of the cam 110.

This cam 110 is designed, as shown in Fig. 1, to reciprocate the head 48 several times during each cycle of operation of 30 the machine, and these reciprocations are so timed as to occur when the picker 34 is in position over the respective magazines and in the lift-depositing position. The object of these reciprocations is to 35 effect the depression of the picker into position to be engaged by the uppermost lift in whatever magazine it is acting upon, and also to depress it when in its depositing position at the assembling station.

40 In order that the picker shall be so actuated in the positions just indicated, the head 48 is provided with a plurality of downwardly projecting rigid pins 328 (Figs. 1, 2, 3, and 15) and with a movable spring-cushioned pin 330. The pins 328 are located upon the head 48 in positions directly above the several magazines, so that if the picker occupies a position above any of the magazines at the time the head is reciprocated, one of the pins 328 will engage the upper end of the picker rod 230, as shown in dotted lines in Fig. 15, and force it downwardly in opposition to the spring 240, whereby the picker plate 226 is depressed. 45 The adjustable set screw 220 (Fig. 16) associated therewith engages the cam surface of the clamp-releasing pawl 186 and depresses it into such position that the clamp 144 of that particular magazine is released by the 50 movement of the arm 180 of the bell-crank 176, as hereinbefore explained. When the reciprocating head 48 is elevated, the spring 240 raises the picker rod 230 and associated picker plate 226, to which the uppermost

lift of the stack adheres. During this movement, the clamp-releasing pawl 186 is permitted to be raised by its spring 200, whereby the clamp 144 is restored to its clamping position. Thus, the picker is actuated to effect the removal of a lift in any magazine. 65

The spring-cushioned pin 330 projects downwardly from the head 48 in such position as to engage the upper end of the picker rod 230 when it occupies its lift-depositing position. The spring-cushioned pin 330, 70 above mentioned, is slidably mounted in a sleeve 334, comprising an integral part of the head 48, and a spring 336 surrounds said rod within a recess 338 in said sleeve, the upper end being positioned against a screw-threaded abutment or plug 340 at the upper end of the sleeve and the lower end resting against a collar 342 that is pinned to the pin 330 within the recess 338. The pin 330, 75 therefore, is normally maintained in its lowermost position with respect to the head 48.

If the picker occupies its lift-depositing position at the time the head is reciprocated, the spring-cushioned pin 330 is brought into engagement with the upper end of the picker 80 rod 230, and therefore yieldingly effects its depression, whereby the picker-plate 226 and the transferred lift which adheres thereto is forced downwardly to place or deposit the lift upon the fore part 77 of the table 85 74 or upon the pile of lifts that may already be assembled thereon. By reason of the yielding support of the pin 330, the degree of depression of the picker is only such as determined by the height of the heel-pile 90 95 that is being built, the yielding element of the pin 330 being adapted to accommodate the varying heights of the heel-pile being produced.

It is desirable to definitely and positively 105 position the picker arm 232 at the times that the picker is depressed by the reciprocating head 48 whether the picker be located over the magazines or above the assembling station. Therefore, the head is provided 110 with a plurality of guide fingers 346 (Fig. 15) that are angular in form and are suitably secured to the under surface thereof in such positions as to correspond to the positions of rest of the rotating picker. The 115 lower end of each of the guide fingers 346 is provided with a tapering slot 348, which is adapted to receive and positively position the web of the picker arm 232 when the reciprocating head 48 is depressed.

Explanation has already been made of the manner of operation of the gate-cam 36, including the several gates or switches 40, 42, and 44, by means of which the operation 120 of the picker is prescribed and shifted from one magazine to another. In order to render the machine entirely automatic in its action, the operation of said gates or

switches is controlled and regulated in accordance with the height of the heel-pile as it is progressively built. This automatic control is effected by means of the measuring apparatus, which comprises the combined measuring and stripping fingers 50, the toothed cam segment 52, and the adjustable gate or switch pins 54.

Through the agency of this measuring apparatus, the height of the heel-pile is progressively measured after each lift is assembled. This measurement is transmitted to the toothed cam segment, which accordingly actuates the proper gates or switches to modify the operation of the picker and thus automatically produce a decked heel-pile of predetermined dimensions and characteristics.

The measuring apparatus is most clearly illustrated in Figs. 6, 7, 10, 11, 12, 13, 14, 15 and 19, to which reference may now be made. Referring particularly to Figs. 6, 13 and 14, the measuring and stripping fingers 50 are screw-threaded in pairs through 25 upwardly projecting members 354 constituting the free ends of a pair of supporting arms 356 that are pivotally mounted upon pins 358 carried by a block 360. The respective pivotally mounted arms 356 are provided with intermeshing gear segments 362, which serve to insure their mutual and like action.

The block 360 is mounted upon the reduced upper end 363 of a vertically movable rod or spindle 364, which is suitably guided by upper and lower bearings 366 and 368 that are respectively associated with the cross-beams 73 and 70. Intermediate the ends of the spindle 364 is a collar 370 (Figs. 13, 14 and 19) which is pinned thereto, and beneath this collar is a loosely mounted spool 372, which is normally urged against the collar 370 by means of a heavy coil spring 374, that surrounds the spindle 364 and has its lower end supported by means of a collar 376 suitably pinned to said spindle. Between the flanges of the spool 372 is located a plurality of rolls 378 which are pivotally mounted upon the bifurcated end of an arm 380 of a bell-crank that is loosely mounted upon the crank-shaft 84 and which is provided with another arm 382 carrying at its end a pivotally mounted roll 384 engaging a cam path 386 in the face of the cam 104.

The cam 104 is so designed and positioned upon the cam-shaft 82 as to raise and lower the block 360 and the associated measuring and stripping fingers 50 once for each cycle of operation of the machine, it being understood that the block is positively elevated after the spool 372 is brought into engagement with the pinned collar 370, and is depressed through the agency of the spring

374 when the spool 372 is moved downwardly to place the spring under compression.

The pivotally mounted arms 356 and their associated measuring and stripping fingers 50 are also oscillated laterally during each cycle of the machine and in timed cooperation with the raising and lowering movements thereof, so that the fingers are separated before being raised and are moved toward each other into their measuring and stripping position prior to being depressed into engagement with the uppermost lift on the heel-pile being built. These lateral movements of the fingers 50 are effected by means of an arm 390 which forms an integral part of one of the arms 356 and which is connected by a universal joint 392 to one end of a link 394, the other end of which has a universal connection 396 with the upper end of an arm 398. This arm 398 constitutes a part of a bell-crank that is loosely mounted upon the crank-shaft 84 (Figs. 13 and 22) and comprises an arm 400 that carries at its outer end a roll 402 which cooperatively engages a cam path 404 in the cam 106. The cam 106 is designed to effect the lateral swinging movements of the arms 356 and associated fingers 50 in the timed relation hereinbefore set forth.

With the construction just described, the combined measuring and stripping fingers 50 are moved into the position shown in Fig. 6, after each depositing movement of the picker, in which position said fingers are disposed within the notches 228 of the picker plate 226 and in engagement with the exposed surface of the uppermost lift in the pile. This engagement is maintained while the picker is withdrawn vertically, as already explained, whereby the fingers 50 strip the last lift transferred from the picker plate to which it adheres. Inasmuch as the fingers 50 engage the upper surface of the heel-pile, it is evident that they also serve to measure the height thereof and, at the same time, limit the downward movement of the block 360 and spindle 364, in opposition to the spring 374. The vertical position of the block 360, therefore, depends upon the height of the heel-pile as it is progressively built, and is raised step-by-step as each lift is added to the pile, the raising movement of the block and associated measuring and stripping fingers 50 by means of the cam 104, being sufficient at each cycle of operation to accommodate the greatest height of heel that the machine is capable of building.

After the picker has been withdrawn and the transferred lift stripped therefrom by the fingers 50, said fingers are withdrawn laterally by means of the cam 106 and the associated mechanism already described,

after which the block 360 and fingers 50 are elevated to their upper limit of movement. As soon as another lift has been placed upon the pile, the fingers 50 are again moved inwardly and downwardly to their stripping and measuring position, upon the lift last deposited, as shown in Fig. 6, which cycle of operation continues periodically throughout the operation of the machine.

In order to control the actuation of the gates or switches 40, 42 and 44 in accordance with the height of the heel-pile as it is built, means is provided for adjusting the toothed cam segment 52 in accordance with the movements of the measuring block 360 and fingers 50. This means comprises a lever 410 (Figs. 12 and 15) that is pivotally mounted intermediate its ends upon a stud 412 and has at its outer end a pin-and-slot connection 414 with a plurality of ears 416 that are fixed to the block 360. The other end of the lever 410 is bifurcated and carries a plurality of rolls 420. These rolls 25 are positioned between the flanges of a spool 422 that forms a part of a sleeve 424 that is adapted to slide vertically upon a bearing bushing 426 that is supported by the plate or table 74 for the purpose of journaling the central shaft 112. The toothed cam segment 52 forms an integral part of the sleeve 424 and spool 422 and is provided with as many upwardly projecting cams or teeth 428 as there are adjustable gate-pins 35 54. These cam projections 428 are spaced, the one from the other, in such relation as to respectively cooperate with the several pins 54 and their working surfaces are radially disposed with respect to the central shaft.

For the purpose of effecting the engagement of the cams 428 and the adjustable gate-pins 54, and therefore the actuation of the respective gates or switches 40, 42 and 44 provision is made to periodically oscillate the cam segment 52 back and forth in proper timed cooperation with the actuation of the picker. The sleeve 424 of the cam segment 52 is therefore provided with an arm 430 which has a universal connection 432 to one end of a link 434, the other end of which has a universal connection 436 with the upper end of an arm 438. The arm 438 (Fig. 18) forms a part of a bell-crank 55 55 that is rotatably mounted upon the crank-shaft 84 and which is provided with another arm 440 that carries at its outer end a roll 442 cooperatively engaging a cam path 444 in the face of the cam 100. The cam 60 100 is designed to effect a periodic oscillation of the cam segment 52 at each cycle of operation of the machine. From the foregoing description, it is clear that for each height of the heel-pile being built, there is a 65 corresponding definite vertical position for

the cam segment 52 and, moreover, at each cycle of operation of the machine, said cam segment is oscillated to and fro.

In order to make use of these movements of the cam segment to automatically effect the actuation of the gates or switches 40, 42 and 44 and therefore the operation of the picker, the pins 54 that are associated with the respective gates or switches are initially adjusted in position so as to project downwardly different predetermined distances in accordance with the height requirement of the various decks of the heel-pile to be built. The pin 54 associated with the gate or switch 40, that is located adjacent the first magazine, is preliminarily set to such a distance that it will be engaged by the left-hand cam 428 (Fig. 12) during each counter clockwise rotation of the cam segment 52, only while and until the first deck of the heel is built to the required height. At each cycle of operation of the machine during the building of the first deck of the heel-pile the above mentioned rotation of the cam segment 52 throws the gate or switch 40 into its open position, as shown in Fig. 7, so that the picker is caused to remove a lift from the first magazine during each of its operating cycles. As the height of the heel progressively increases, the cam segment 52 is proportionately lowered until, when the required height is attained, the segment has been lowered to such an extent that it fails to engage the pin 54 of the first gate or switch 40. Therefore, this gate or switch is left in its closed position, as shown in Fig. 10, so as to cause the picker to pass by the first magazine without removing a lift therefrom.

The pin 54 of the second gate or switch 42 is initially set below the lower end of the first pin a distance which corresponds to the requisite height of the second deck of the heel to be built; and similarly, the pin of the third gate or switch 44 is positioned below the second pin a distance corresponding to the required height of the third heel deck. Therefore, it is evident that while the first deck is being built, all three of the gates or switches 40, 42 and 44 are actuated at each cycle. The operation of the second and third gates, however, is of no consequence, since the position of the first gate 40 determines the operation of the picker. Having built the first deck of the heel, the second and third gates 42 and 44 are periodically actuated in the manner described, although the actuation of the second gate only is effective in determining the operation of the picker. When the required height of the second deck 65 125 has been reached, the cam segment 52 has been correspondingly lowered to such a degree that it no longer engages the pin 54 of the second gate 42 and therefore this gate, as well as the gate 40, is left in its 130

closed position, while the third gate 44 only is actuated to cause the picker to operate upon the third magazine.

In a similar manner, the actuation of the 5 third gate or switch 44 is discontinued and said gate left in its closed position, together with the first and second gates, as shown in Fig. 9, when the third deck of the heel-pile and, therefore, the final height of the 10 entire pile, has reached the requisite height. Under these conditions, the cam-roll 266 is caused to traverse the entire length of the peripheral cam path 280 of the gate-cam 36, thus causing the picker, during its next 15 revolution, to pass by the several magazines until it reaches its ejecting position, as illustrated in Fig. 9. The operation of the ejecting apparatus will be hereinafter described in detail.

20 The coating of paste applied to the bottom of the picker-plate 226 by the paste roller 276 is apt to be meagre and not uniformly distributed, so that, although sufficient to pick up a lift from a magazine and 25 transfer it to the assembling station, it is insufficient to rely upon to secure together the component lifts of the heel-pile in a satisfactory manner. It is necessary, therefore, to provide means for applying paste to the 30 upper surface of each lift after it has been transferred and deposited upon the pile.

Referring particularly to Figs. 1, 2, 6, and 35 12, this means is the paste-applying device 56 which comprises a plate 450 having a pad 452 secured to the lower surface thereof. The plate 450 is attached to the lower end of a rod 454 that projects upwardly through bearings 456 and 458 that are associated with a swinging supporting arm 460, the latter being clamped to the upper 40 end of a rotatable sleeve 461 that surrounds one of the head supporting rods 78 by means of bolts 462. The rod 454 is provided with a fixed collar 464 against which the upper 45 end of a coil spring 466 operates, and the lower end of said spring rests against the lower bearing 458. The collar 464 and, in fact, the whole mounting of the paste-applying device 56, is similar to that of the 50 picker 34 already described, and is such that the paste applying plate 450 and associated pad 452 are normally maintained in their raised position.

In order to apply paste to the heel-lifts as 55 they are assembled, the supporting arm 460 and associated paste applying device 56 are periodically swung from a position over a paste-pot 468 as shown in Fig. 6, to a position over the heel-pile or section that is 60 being built, as shown in Fig. 7. This periodic swinging movement is accomplished by means of a bell-crank 470 (Figs. 2 and 12) which is clamped by means of bolts 472 to the rotatable sleeve 461 surrounding the 65 head supporting rod 78, to which the sup-

porting arm 460 of the paste applying device is also clamped. This bell-crank 470 is provided with an arm 474 which has a universal connection 476 with one end of a link 478 the other end of which has a universal 70 connection 480 to the upper end of an arm 482. The arm 482 forms a part of a bell-crank that is rotatably mounted upon the crank shaft 84 and is provided with an arm 484 (Figs. 2 and 13) that carries a roll 486 75 which is maintained by means of a spring 488 against the periphery of the cam 108. The cam 108, through the agency of the connections just described, is adapted to periodically swing the paste-applying device 56 from the paste-pot 468 to the assembling station.

The paste-applying device 56 is immersed 80 in the paste-pot 468 by means of a bell-crank 492 that is pivotally mounted upon 85 a stud 494 upon the side of the swinging supporting arm 460, and the rounded end 496 of one of the arms of said bell-crank is adapted to rest against the upper surface of the paste-applying plate 450. The other 90 arm of the bell-crank 492 is adapted, when the paste-applying device is in position over the paste-pot 468, to be engaged by an upper hooked end 498 of a pull-down rod 500 95 (Figs. 1 and 14) which is slidably mounted in a fixed bearing 502 and has a pivotal connection 504 with a lug 506 that is secured to the bell-crank 320 that effects the reciprocation of one of the head supporting rods 78. It is evident, therefore, that whenever 100 the paste-applying device 56 occupies a position over the paste-pot 468 at the time that the reciprocating head 48 is moved downwardly, the paste-applying device is 105 immersed in the paste-pot through the agency of the connections just described.

Having thus immersed the paste-applying device 56, it is swung over into its position over the last lift deposited upon the heel-pile that is being built. This position is 110 such that the upper end of the rod 454, to which the paste-applying plate is secured, is located directly beneath the spring-cushioned pin 330 on the reciprocating head 48, a position similar to the position occupied by the picker supporting rod 230 when the picker is over the assembling station. Therefore, when the reciprocating head 48 is again dropped, the spring-cushioned pin 115 330 is brought into engagement with the upper end of the rod 454, as shown in Fig. 20, whereby the paste-applying device 56 is depressed into engagement with the uppermost lift in the heel-pile, during which operation the exposed surface of the uppermost lift is thoroughly coated with paste. As the reciprocating head 48 is again elevated, the spring 466 raises the paste-applying device from the heel-pile, as will be 120 understood. The paste-applying device is 125 130

then swung back to its initial position over the paste-pot 468 where it is again immersed preparatory to the next cycle of operation, during which it applies paste to the next 5 lift superposed upon the pile.

Obviously, it is undesirable to coat the upper surface of the table 74 at the assembling station with paste before the first lift is deposited, and also to coat the upper 10 surface of the final lift upon the heel-pile and, therefore, the stops 58 and 60 are employed, the construction and operation of which will now be described.

Referring particularly to Figs. 12 and 15, 13, the block 360 is provided with a plurality of downwardly projecting ears 510 and 512. The ears 510 are pivotally connected by means of a link 514 with an arm 516 of a bell-crank that is rotatably mounted upon a stud 518 which is suitably carried by the cross beam 73. The bell-crank is provided with an elongated arm 520 that extends across the front of the machine and carries at its end an adjustable set screw 20 which constitutes the stop 60. The stop 58 comprises a lever that is rotatably mounted upon a stud 522 and is pivotally connected to the ears 512 by means of a link 524.

Before any lifts are deposited upon the 30 table 74, at which time combined stripping and measuring fingers 50 occupy their lowermost positions and rest upon said table, the stops 58 and 60 are in positions, as shown in Fig. 14. The end of the stop 58, therefore, lies in the horizontal plane of the end of an arm 526 which constitutes a part of the bell-crank 470 that is clamped to the sleeve 461 which serves to swing the paste-applying device 56 between its two operative 40 positions. When the stop 58 occupies the position shown in Fig. 14, it becomes impossible for the spring 488 to move the paste-applying device from its position over the paste-pot, and therefore said device is prevented from applying paste to the upper surface of the table 74. However, as soon as the first lift is deposited upon the table, the measuring fingers 50 and, therefore, the block 360 are moved to a slightly 50 elevated position, which movement is sufficient to depress the stop 58 below the plane of the stop-arm 526, so that during the subsequent operation of the machine, the paste-applying device operates, through its normal cycles, to periodically apply paste to the lifts as they are progressively assembled to form the heel-pile.

As the heel-pile is thus built up lift by 60 lift, the stop 58 is moved downwardly in steps, while the stop 60 is intermittently raised until the heel-pile reaches its final height, under which conditions the stop 60 is positioned in front of the stop-arm 526. Thus, the paste-applying device is prevented 65 from moving over the assembling sta-

tion and coating the upper surface of the final and uppermost lift with paste.

Attention is now directed particularly to Figs. 9 and 13, which clearly illustrate the apparatus by means of which a complete 70 heel-pile is discharged from the machine, and which comprises the ejector 62 which is actuated by means of the picker 34 after all of the lifts have been assembled and the cam roll 266 in travelling the peripheral 75 cam-path 280 of the gate-cam 36 brings the picker into the position shown in Fig. 9.

The ejector 62 comprises an arm having a curved heel-engaging end portion 530, and said arm is pivotally mounted upon a stud 80 532 that projects upwardly from the table 74. Integrally associated with the ejector-arm 62 by means of a hub 534 is a short arm 536 having a roll 538 pivoted at its outer end. A spring 540 is suitably attached to the ejector 62 and normally maintains it, as shown in Fig. 9, in such a position that when the heel-pile is completed and the cam-roll 266 traverses the peripheral cam path of the gate-cam 36, the roll 90 538 of the short-arm 536 is engaged by the boss 260 that forms a part of the picker actuating link 254. As the operation of the picker 34 continues from the position shown in Fig. 9, the short-arm 536 and the connected ejector 62 are actuated in a counter-clockwise direction whereby the completed heel at the assembling station is kicked off or ejected therefrom. After this operation and subsequent to the passage of the picker, 100 the ejector 62 is returned to its normal position by means of the spring 540, and the various parts of the machine are in position to build another heel-pile. Obviously, the 105 operation of the ejector is entirely automatic and is dependent, through the intermediary of the measuring apparatus, upon the height of the heel being built.

Under certain operating conditions, particularly when the paste is slow-drying in 110 character, it may be found desirable to provide means for holding the lifts of the heel-pile firmly in position, while the combined measuring and stripping fingers 50 are being laterally withdrawn, in order to obviate 115 the tendency of the lifts to slide and skew, one upon the other. To accomplish this result, an auxiliary device or attachment is provided which may be conveniently embodied in the machine, as illustrated in 120 Figs. 24, 25, 26 and 27.

This device comprises the clamping and 125 positioning finger 64, the end of which is very thin and adapted to rest upon the uppermost heel-lift in the pile being assembled, as shown in Fig. 24, at the time the stripper fingers 50 are withdrawn. The finger 64 is secured to the end of an arm 546 that is pivotally mounted upon a horizontal stud 548 adjacent to an oppositely 130

projecting actuating arm 550 that is pinned thereto. The finger-carrying arm 546 is provided with a boss 552 which is located just beneath a corresponding boss 554 upon the arm 550. Threaded into the last mentioned boss 554 is an adjustable set screw 556, the head of which is normally held in engagement with the boss 552 by means of a torsional spring 558 that surrounds the hub of the arm 546 and is so arranged as to tend to actuate the stripping finger 64 downwardly until the engagement of the set screw 556 and the lug 552 is effected.

The stud 548 is mounted in a yoke member 560 that is conveniently pivoted upon an extended portion 562 of the stud 532, which serves as a bearing for the ejector 62. The yoke member 560 is provided with a laterally extending pin 564, to which is attached one end of a coil spring 566, having its other end secured to an arm 568 forming a part of the arm 550. The arm 550, therefore, is normally maintained in its raised position.

In order to periodically oscillate the pivotally mounted yoke member 560 it is provided with an arm 570 having an aperture 572 in the end thereof, through which a rod 574 loosely projects. One end of the rod 574 is provided with a plurality of adjustable nuts 576, while the other end thereof is bifurcated and connected by means of a universal joint 578 to one end of the link 434 which is attached to and oscillates the cam-segment 52. A spring 580 surrounds the rod 574, and its respective ends bear against the bifurcated end of said rod and against the apertured end of the arm 570.

With this construction, it is evident that the yoke member 560 and its associated clamping and positioning finger 64 are periodically oscillated about the pin 532 in accordance with the oscillations of the cam segment 52, and, moreover, the outward or retracting movement of said finger 64 is positively effective through the agency of the rod 574, while the inward movement thereof is yielding in character and effected through the agency of the spring 580. Thus, if the clamping and positioning finger 64 accidentally encounters a lift or other obstacle during its inward movement, the spring 580 yields and prevents the breakage of parts.

In order to actuate the clamping and positioning finger 64 in a vertical direction to cause it to engage and disengage the heel-pile being built, the arm 550 is provided at its end with a pivotally mounted roll 582 that is adapted to cooperatively engage a switch-cam associated with a bracket 584 that is conveniently attached to the upper end of the side frame 66 by means of bolts 586. The bracket 584 has attached thereto a block 588 having an inclined lower cam surface 590 with which the cam-roll 582 of

the arm 550 is adapted to engage when the clamping and positioning finger 64 is moved outwardly. By reason of this engagement, the arm 550 is forced downwardly, and therefore, through the engagement of the set screw 556 and the lug 552, the arm 554 and associated positioning and clamping finger 64 is correspondingly raised during the withdrawal movement.

Beneath the inclined cam surface 590, and pivotally mounted upon the bracket 584 is a cam switch 592 (Fig. 27) which is normally maintained in its raised position in engagement with the cam surface 590 by means of a torsional spring 594 that suitably cooperates with the pivot pin 596 of said cam switch.

As the cam roll 582 moves downwardly along the cam surface 590, it depresses the cam switch 592 into the position shown in dot-and-dash lines in Fig. 27. The subsequent movement of the cam roll 582 permits the spring pressed cam switch 592 to be restored to its normal horizontal position, whereupon it serves as a cam to prescribe the movement of the cam roll 582, as said roll is moved to the right (Fig. 27) at the time that the finger 64 is oscillated back towards its lift engaging position. Inasmuch as the roll 582 is thus caused to move in a horizontal plane throughout its engagement with the lower surface of the cam switch 592, it is clear that the lift positioning and clamping finger 64 is held in its raised position until the roll 582 runs off of the cam switch 592 and into the position shown at the right in dotted lines in Fig. 7. As soon as the cam roll 582 is unrestrained by the cam switch 592, the spring 566 causes the arm 550 and associated cam roll 582 to be raised into engagement with the horizontal portion of the cam surface 590. At the same time, the torsional spring 558, always tending to maintain the lug 552 of the arm 546 in engagement with the set-screw 556, causes the finger 64 to be depressed into engagement with the uppermost lift upon the heel-pile.

Assuming the lift assembling and clamping finger 64 to occupy its initial position, in which it rests upon the upper surface of the table 74, the operation of the auxiliary device or attachment, just described, with respect to the other parts of the machine with which it cooperates, is as follows: The first lift deposited by the picker 36 is placed upon the assembling table 74 and the thin end of the finger 64. The measuring and stripping fingers 50 are then brought into position to hold the lift, after which the clamping and positioning finger 64 is withdrawn, both outwardly and upwardly, and immediately restored to a position in which it engages the upper surface of the lift and clamps it positively in position. While the

lift is thus firmly held in position, the stripping fingers 50 are withdrawn laterally, during which action, displacement of the lift is prevented. When the picker returns with another lift, it is assembled upon the first lift deposited and upon the positioning finger 64 in its clamping position, after which the stripping fingers are brought into position and the finger 64 withdrawn and again replaced in clamping position, in the manner already described.

The cycle of operation continues throughout the progressive building of the heel-pile, and by reason thereof, regular and well-shaped heels are produced, since no skewing or displacement of the component lifts thereof is possible during the building operation.

After the final lift has been deposited upon the heel-pile which is thus completed, the ejector 62 is actuated, in a manner already described, to effect the discharge thereof. In order to insure the free and unobstructed discharge of the heel-pile, means is provided for withdrawing the clamping and positioning finger 64 from its engagement therewith. This withdrawal is effected through the agency of a lug 598 with which the arm of the ejector 62 is provided. Associated with the yoke member 560 and projecting laterally therefrom is a lug 600, through which an adjustable set screw 602 projects into cooperative relationship with the lug 598 of the ejector. When the ejector 62 is actuated to effect the discharge of the completed heel-pile, the lug 598 is brought into engagement with the end of the set screw 602, whereby the yoke member 560, together with all of the parts associated therewith, is rotated outwardly in a counter-clockwise direction. During this movement, the clamping and positioning finger 64 is also moved in a similar direction and at the same time, by reason of the cooperative engagement of the roll 582 with the inclined cam surface 590, said finger 64 is also moved into its elevated position. In this manner, the clamping and positioning finger 64 is withdrawn from the path of the heel-pile at the time of its ejection and discharge.

Having described the construction and operation of the preferred embodiment of the invention, that which is claimed as new is:

1. A machine having, in combination, a plurality of magazine for containing stacks of thin blanks of varying thicknesses and means adapted to engage the faces of the blanks for successively removing a plurality of blanks from each of the magazines in turn and depositing them in superposed relation.

2. A heel building machine having, in combination, a plurality of magazines for containing stacks of thin lifts of varying thicknesses and graded sizes, and means acting successively upon lifts in each magazine

for removing lifts therefrom, one at a time, and depositing them in superposed relation to form a decked heel.

3. A heel building machine having, in combination a plurality of magazines for containing lifts, means for successively removing lifts, one at a time, from any of the magazines, and means for modifying the operation of said removing means to determine the magazine upon which it shall act.

4. A heel building machine having, in combination, a plurality of magazines for containing lifts, means for successively removing a plurality of lifts from one of the magazines, and automatic means for modifying the operation of said removing means to cause it to act upon the lifts in another magazine.

5. A heel building machine having, in combination, a plurality of magazines for containing lifts, means for successively removing lifts from one of the magazines and depositing them in a pile in superposed relation, and means dependent upon the height of said pile for causing said removing and depositing means to act upon lifts in another of said magazines.

6. A heel building machine having, in combination, a plurality of magazines for containing lifts, means for removing lifts, one at a time, from one of the magazines and depositing them in a pile in superposed relation, means for measuring the height of the pile after each lift is deposited, and means controlled by said last means for causing said removing and depositing means to act upon the lifts in another magazine.

7. A heel building machine having, in combination, a plurality of magazines for containing lifts, a single picker for successively removing lifts from one of the magazines and depositing them in a pile in superposed relation, and means for causing said picker to act upon the lifts of another magazine when the pile has reached a predetermined height.

8. A heel building machine having, in combination, a plurality of magazines for containing lifts of graded sizes, means for successively removing lifts of one size from one of said magazines and depositing them in a pile in superposed relation, and automatic means dependent upon the height of the pile for causing said removing and depositing means to successively act upon the different sized lifts of the remaining magazines, whereby a decked heel is built.

9. A heel building machine having, in combination, a holding means for containing a supply of thin lifts of varying thicknesses, and means for successively removing therefrom and depositing in a pile a sufficient number of lifts to form a pile of predetermined height.

10. A heel building machine having, in combination, a magazine for containing a supply of lifts, means for successively removing a plurality of said lifts and depositing them in a pile, one upon the other, and means for determining the height of said pile and discontinuing the operation of said removing and depositing means in accordance therewith. 5
11. A heel building machine having, in combination, a magazine for containing a supply of lifts of varying thicknesses, and means including measuring mechanism and a picker for removing lifts successively from said magazine and depositing them in a pile in superposed relation to build a heel section of predetermined height. 10
12. A heel building machine having, in combination, a magazine for containing a supply of lifts of varying thicknesses, means for removing lifts successively from said magazine and depositing them in a pile in superposed relation, and means dependent upon the height of the pile for determining the number of lifts that shall be superposed. 15
13. A heel building machine having, in combination, a plurality of magazines for containing lifts, means for successively removing a plurality of lifts from each of the magazines and depositing them in a pile in superposed relation, means dependent upon the height of the pile as it is built for causing said removing means to act upon the lifts in the several magazines one after the other, and adjustable means for determining the operation of said last named means. 20
14. A heel building machine having, in combination, a plurality of magazines for containing lifts of graded sizes, a picker device for removing lifts successively from any of said magazines and assembling them in a pile in superposed relation, and automatic means including a plurality of adjustable pins and dependent upon the height of the pile as it is built for causing the operation of said picker device to be shifted from one magazine to another to produce a decked heel of predetermined dimensions. 25
15. A heel building machine having, in combination, a plurality of stationary magazines for containing lifts, and automatically controlled picker means for successively removing a plurality of lifts from each of the magazines in turn and assembling them one after the other in a pile in superposed relation. 30
16. A heel building machine having, in combination, a plurality of magazines for containing lifts, an automatically controlled picker means for successively removing a plurality of lifts from each of the magazines in turn and assembling them one after the other in a pile in superposed relation, and adjustable means for measuring the height of the pile as it is built and causing said picker device to operate upon the several magazines in turn in accordance therewith. 35
17. A heel building machine having, in combination, a plurality of magazines for containing lifts, means for transferring lifts from the magazines and superposing them in a pile at an assembling station, and a cam device controlled automatically in accordance with the height of the pile being built for determining the operation of said transferring means. 40
18. A heel building machine having, in combination, a plurality of magazines for containing lifts, means for transferring lifts from the magazines and superposing them in a pile at an assembling station, and a multiple-pathed cam device for governing the operation of said transferring means and embodying a plurality of gates or switches actuated in accordance with the height of the pile as it is built for causing said transferring means to act successively upon the lifts in the respective magazines. 45
19. A heel building machine having, in combination, a plurality of magazines for containing lifts, means for transferring lifts from the magazines and superposing them in a pile at an assembling station, a multiple-pathed cam device for governing the operation of said transferring means and embodying a plurality of gates or switches for determining the cam path to be employed, a plurality of pins respectively associated with said gates or switches, and means positioned in accordance with the height of the pile as it is built for engaging said pins and effecting the actuation of said gates or switches, whereby the operation of said transferring means is shifted automatically from one magazine to another. 50
20. A heel building machine having, in combination, a plurality of magazines for containing lifts, means for transferring lifts from the magazines and superposing them in a pile at an assembling station, a multiple-pathed cam device for governing the operation of said transferring means and embodying a plurality of gates or switches for determining the cam path to be employed, a plurality of pins respectively associated with said gates or switches, and an oscillatory member adapted to be progressively lowered in proportion as the height of the pile is increased, for engaging said pins and actuating said gates or switches to automatically shift the operation of said transferring means from one magazine to another. 55
21. A heel building machine having, in combination, a plurality of magazines for containing lifts, means for transferring lifts from one or more of said magazines and assembling them in a superposed pile, and a stripper finger independent of the transferring means for engaging the upper surface of the pile. 60

of said pile after each lift is deposited thereon.

22. A heel building machine having, in combination, folding means for containing lifts, means for transferring lifts from said holding means and assembling them in a superposed pile, movable means independent of the transferring means for holding the pile in position while the transferring means 10 is withdrawn, and means acting after each lift is deposited upon the pile for actuating said movable means into engagement with the upper surface of said pile.

23. A heel building machine having, in combination, holding means for containing lifts, means for transferring lifts from said holding means and assembling them in a superposed pile, and a pair of vertically reciprocal and horizontally oscillatable strips 20 per fingers for engaging the upper surface of each lift that is deposited upon the pile and holding the pile in position while the transferring means is removed.

24. A heel building machine having, in combination, holding means for containing lifts, means for transferring lifts from said holding means and assembling them in a superposed pile, a stripper finger independent of said transferring means, means for periodically reciprocating said finger in the direction of the height of the heel for engaging the upper surface of each lift deposited thereon, and yielding means associated therewith to accommodate the operation of said stripper finger to the progressively increased heights of the pile.

25. A heel building machine having, in combination, a magazine for containing heel lifts, and a picker device adapted to rotate 40 periodically through a complete revolution and to transfer a lift from said magazine to an assembling station during each revolution to produce a heel.

26. A heel building machine having, in combination, a plurality of magazines for containing heel lifts and a picker device adapted to rotate periodically through a complete revolution, during which it removes a lift from one of the magazines, 50 transfers it to an assembling station and deposits it therein.

27. A heel building machine having, in combination, a magazine for containing heel lifts, a picker device adapted to rotate 55 through successive complete revolutions, and means for causing said device to remove a lift from the magazine and deposit it at an assembling station at each cycle of operation.

28. A heel building machine having, in combination, a magazine for containing heel lifts, a picker device adapted to rotate through successive complete revolutions, means for causing said device to pause over 65 said magazine and over an assembling sta-

tion, and means acting during said pauses for causing said picker device to remove a lift from said magazine and to deposit it at said assembling station.

29. A heel building machine having, in combination, a plurality of magazines for containing heel lifts, a picker device adapted to rotate through successive complete revolutions, and means for causing said device to successively remove a plurality of lifts 75 from each of the magazines in turn and deposit them one after the other in a superposed pile at an assembling station.

30. A heel building machine having, in combination, a plurality of magazines for 80 containing heel lifts, a picker device adapted to rotate through successive complete revolutions, an automatic means for causing said device to remove lifts successively from any 85 of the magazines and deposit them in a superposed pile at an assembling station, and means controlled in accordance with the height of the pile as it is built for causing said device to act upon the lifts in the respective magazines in turn. 90

31. A heel building machine having, in combination, a magazine for containing lifts, a picker device adapted to periodically rotate through complete revolutions, means for applying paste to the picker device during its movement, means for subsequently depressing said device into engagement with the uppermost lift in said magazine whereby said lift is caused to adhere thereto, and means for causing said device to deposit said lift at an assembling station. 95

32. A heel building machine having, in combination, a magazine for containing lifts, a picker device adapted to periodically rotate through complete revolutions, a paste 105 roller in the path of movement of said picker device for applying paste thereto, means for causing said picker device to pause in its movement over the magazine and later over an assembling station, and means for depressing said device into engagement with the uppermost lift in said magazine, whereby said lift is picked up thereby, and for depressing said device to effect the deposition of said lift at the assembling station. 110

33. A heel building machine having, in combination, a magazine for containing lifts, a paste picker adapted to be rotated periodically through complete revolutions, means for coating the paste picker with paste, means for causing said picker to pick up the uppermost lift in the magazine and deposit it at an assembling station, and means for engaging said deposited lift to hold it in position while the paste picker is withdrawn therefrom. 115

34. A machine having, in combination, means for holding blanks, a device for transferring the blanks successively from said holding means and depositing them in 120

a pile in superposed relation at an assembling station, and means for applying paste to the exposed surface of each blank after it is deposited.

5 35. A heel building machine having, in combination, a magazine for containing lifts, means for transferring lifts successively from said magazine and depositing them in a pile in superposed relation, and
10 means acting after each transferring movement for applying paste to the exposed surface of the uppermost lift in the pile.

36. A heel building machine having, in combination, means for holding a supply of lifts, means for transferring lifts successively from said holding means to an assembling station and depositing them in a pile, and a periodically actuated paste applying device for coating with paste the
20 exposed surface of each of the deposited lifts.

37. A heel building machine having, in combination, means for holding a supply of lifts, a paste picker device for transferring lifts successively from said holding means and depositing them in a pile in superposed relation, means for applying paste to the picker device prior to its action upon the lifts in the holding means, and means
25 for applying paste to the exposed surface of each lift after it is deposited upon the pile.

38. A heel building machine having, in combination, means for holding a supply of lifts, means for transferring lifts successively from said holding means and depositing them in a pile in superposed relation, a paste-pot, and a paste applying device periodically immersed in said paste-pot and moved into engagement with the exposed
40 surface of each of the superposed lifts after it is deposited.

39. A heel building machine having, in combination, means for holding a supply of lifts, and means for transferring lifts successively from said holding means, depositing them in a pile in superposed relation and applying paste to each of the lifts after it is deposited.

50 40. A heel building machine having, in combination, means for holding a supply of lifts, a transferring picker device adapted to rotate through successive complete revolutions and to transfer a lift from the holding means to an assembling station at each cycle of operation and means acting at each cycle of operation to apply paste to the last transferred lift at the assembling station.

60 41. A machine having, in combination, means for holding a supply of blanks, means for transferring blanks successively from said holding means and depositing them in a pile in superposed relation, and means
65 independent of said transferring means for

applying paste to the upper surface of all but the last blank so transferred and deposited.

42. A heel building machine having, in combination, means for holding a supply of lifts, means for transferring lifts successively from said holding means and depositing them in a pile in superposed relation, means normally acting to apply paste to the upper surface of each lift after it is deposited, and means to prevent said last means from applying paste to the last lift of the pile.

43. A heel building machine having, in combination, means for holding a supply of lifts, means for transferring lifts successively from said holding means and depositing them in a pile in superposed relation, means normally acting to apply paste to the upper surface of each lift after it is deposited, and means dependent upon the height of the pile for preventing the operation of said last means.

44. A heel building machine having, in combination, means for holding a supply of lifts, a support, means for transferring lifts successively from said holding means and depositing them upon said support in superposed relation, paste applying means normally acting to move into the depositing position at each cycle of operation of the transferring means to apply paste to each of the deposited lifts, and automatic means for preventing said last means from operating to apply paste to the support before any lifts have been deposited.

45. A heel building machine having, in combination, a magazine for containing lifts, a support, a picker device adapted to move over said magazine and said support for transferring lifts successively from one to the other, a paste applying device movable periodically into a position over said support and a reciprocating head for simultaneously depressing the picker device into engagement with the uppermost lift in the magazine and depressing the paste applying device over said support and for subsequently depressing the picker device to effect the deposition of the transferred lift upon said support.

46. A heel building machine having, in combination, means for holding a plurality of lifts, a paste picker for successively transferring lifts from said holding means and depositing them in a pile in superposed relation, a stripper device for engaging the upper surface of each lift upon the pile as it is built for stripping the transferred lift from the paste picker as it is withdrawn, and means for holding the pile in position while the stripper device is removed.

47. A heel building machine having, in combination, means for holding a plurality of lifts, a picker device for successively

- transferring lifts from said holding means and depositing them in a pile in superposed relation, a plurality of laterally movable stripper fingers for engaging the upper surface of each lift deposited upon the pile to strip the lift from the picker device when it is withdrawn, and a clamping member for holding the pile in position while the stripper fingers are laterally removed.
48. A heel building machine having, in combination, means for holding a supply of lifts, a paste picker device including a notched plate for transferring lifts successively from said holding means and depositing them in a pile in superposed relation, and a stripper finger movable into the notch of said picker plate for engaging the upper surface of each lift as it is deposited for stripping the lift from said plate when the picker is withdrawn.
49. A machine having, in combination, a magazine for containing a supply of blanks normally clamped therein, a picker device for engaging and withdrawing the endmost blank from the magazine, and means co-operatively engaged by said picker device for temporarily unclamping the blanks in the magazine at the time the picker acts thereon.
50. A heel building machine having, in combination, a magazine for containing a stack of lifts, means tending to constantly feed the stack towards one end of the magazine, a clamp associated with the magazine normally adapted to clamp the lifts against the operation of said feeding means, a picker periodically movable into engagement with the endmost lift in the stack for removing said lift therefrom, and means rendered operable by the operation of said picker for temporarily releasing said clamp to permit the operation of the feeding means and the removal of the uppermost lift.
51. A heel building machine having, in combination, a plurality of magazines for containing lifts, means tending normally to clamp the lifts therein, a picker for removing lifts from any one of said magazines, and selective means for unclamping the lifts in the magazine upon which the picker operates.
52. A heel building machine having, in combination, a plurality of magazines for containing lifts, means for normally clamping the lifts in each of the magazines, a picker for removing lifts from any of the magazines, means associated with each magazine and periodically actuated in a direction to effect the release of the clamping means, and means cooperating with the picker for causing one of said last means to release the clamp of the magazine upon which the picker operates.
53. A heel building machine having, in combination, means for holding a supply of lifts, means for successively transferring lifts from the supply and assembling them in a pile in superposed relation, means for supplying paste between said lifts, and means dependent upon the height of the pile for effecting its ejection.
54. A heel building machine having, in combination, means for holding a supply of lifts, means for successively transferring lifts from the holding means and superposing them in a pile, means for securing the lifts together, and automatic means dependent upon the height of the pile for effecting its ejection.
55. A heel building machine having, in combination, means for holding a supply of lifts of varying thicknesses, means for transferring lifts successively from said supply and assembling them in a superposed pile, means for securing together the component lifts of the pile, means for measuring the height of the pile as it is progressively built, and means for ejecting the pile when it reaches a predetermined height.
56. A heel building machine having, in combination, a magazine for containing lifts, a picker adapted to rotate successively through complete revolutions to transfer lifts successively from said magazine and deposit them in a superposed pile, means for actuating said picker arranged and adapted to cause said picker to pause over the magazine from which it picks a lift, and means for steadyng and guiding the picker over the magazine during the picking operation.
57. A heel building machine having, in combination, a plurality of magazines for containing stacks of thin lifts of varying thicknesses and graded sizes, and means co-operating in turn with each of said magazines for successively removing therefrom and depositing in a pile a sufficient number of lifts to build a decked heel pile comprising decks of predetermined heights.
58. A heel building machine having, in combination, a plurality of magazines adapted to contain thin lifts of varying thicknesses and graded qualities, means for successively removing lifts of one quality from one of the magazines and depositing them in a pile, and means for causing said removing means to act upon lifts of another quality in another magazine.
59. A heel building machine having, in combination, a plurality of magazines for containing thin lifts of varying thicknesses, a paste-picker adapted to engage the faces of the lifts for successively removing lifts from one of the magazines and depositing them in a pile, means for applying paste to the picker, and means dependent upon the height of the pile for causing the picker to act upon lifts of another magazine.
60. A machine having, in combination, a

plurality of stationary magazines for containing stacks of blanks, movable blank-receiving means adapted to be actuated into a plurality of blank-receiving positions, one position corresponding to each magazine, and means for causing said movable receiving means to cooperate with each of the magazines in turn and to remove a plurality of blanks one at a time from each of the magazines.

61. A heel building machine having, in combination, a plurality of stationary magazines for containing stacks of lifts, and means adapted to be actuated into cooperative relation with said stationary magazines in turn for successively removing a plurality of lifts one at a time from the successive magazines.

62. A heel building machine having, in combination, a plurality of stationary magazines for containing stacks of lifts, a single picker for removing lifts one at a time from any magazine, and means for modifying the operation of said picker to cause it to remove a plurality of lifts from each of the magazines in turn.

63. A heel building machine having, in combination, a plurality of magazines for containing lifts, means for successively removing a plurality of lifts from each magazine in turn and depositing them in a pile, and means dependent upon the height of the pile being produced for causing the operation of said removing means to be shifted from one magazine to another.

64. A heel building machine having, in combination, means for holding a supply of lifts, and means for successively removing therefrom and assembling in a pile only a sufficient number of lifts to form a pile of predetermined height.

65. A heel building machine having, in combination, means for holding a supply of lifts, means for successively removing therefrom and assembling in a pile only a sufficient number of lifts to form a pile of predetermined height, and means for securing together the component lifts of said pile to form a heel.

66. A heel building machine having, in combination, means for holding a supply of lifts, means for successively removing lifts therefrom and assembling them in a pile, and means operating after each lift is deposited for determining the height of the pile so produced and for arresting the operation of said removing and depositing means when said pile is a predetermined height.

67. A heel building machine having, in combination, means for holding lifts, means for removing lifts successively therefrom and assembling them in a pile in superposed relation, and means dependent upon the height of the pile for effecting the ejection thereof.

68. A heel building machine having, in combination, means for holding lifts, means for removing lifts successively therefrom and assembling them in a pile in superposed relation, means for securing together the lifts of the pile, and means for measuring the height of the pile as the lifts are progressively assembled and effecting its ejection when the pile has attained a predetermined height.

69. A heel building machine having, in combination, means for holding lifts, means for removing lifts successively therefrom and assembling them in a pile in superposed relation, means for applying paste to each assembled lift, and means for interrupting the assembly of lifts when the pile has attained a predetermined height.

70. A heel building machine having, in combination, a plurality of magazines for containing lifts of graded characteristics, means for removing lifts successively from any of said magazines and assembling them in a pile, and automatic means adjusted in accordance with the height of the heel or sections thereof to be built for determining the height of the heel or sections thereof during the assembly thereof and for causing the operation of said removing and assembling means to be shifted from one magazine to another.

71. A heel building machine having, in combination, means for holding a supply of lifts, means for transferring lifts from said holding means and assembling them in a pile, and a movable stripper finger independent of the transferring means for engaging the upper surface of said pile after each lift is deposited thereon.

72. A heel building machine having, in combination, rotatably mounted lift-transferring means adapted to rotate periodically through a complete revolution, means for holding a supply of lifts and means upon which heels are assembled, both located in the path of movement of said rotary lift-transferring means, and means for causing said lift-transferring means to remove lifts one at a time from said holding means and to deposit said lifts in a pile upon said assembling means.

73. A heel building machine having, in combination, means for holding a supply of lifts, transfer means adapted to be rotated periodically through a complete revolution, means for causing said transfer means to remove a lift from said holding means and deposit it at an assembling station, and means for stripping the deposited lift from said transfer means.

74. A heel building machine having, in combination, means for holding a supply of lifts, means for transferring lifts successively to an assembling station, and means disposed at said assembling station

and actuated periodically to engage the successive lifts transferred and strip them from said transfer means.

75. A heel building machine having, in combination, means for holding a supply of lifts, a paste picker device for transferring lifts successively from said holding means and depositing them at an assembling station, and means for applying paste to said picker device prior to the transfer of each lift and to the exposed surface of each lift after it has been transferred to the assembling station.

76. A heel building machine having, in combination, means for holding a supply of lifts, means for transferring lifts therefrom and depositing them in a pile at an assembling station, means for engaging the upper surface of each lift upon the pile as it is built for stripping the lift from the transfer means as it is withdrawn, and means for holding the pile in position while the stripping means is removed.

77. A heel building machine having, in combination, a plurality of magazines adapted to contain stacks of lifts, means tending to feed the stacks towards one end of said magazines, means for restraining the operation of said feeding means, means for removing the endmost lift from any of said magazines, and selective means for releasing the restraining means of the particular magazine upon which the removing means operates.

78. A heel building machine having, in combination, means for supporting heel lifts, means for collecting the lifts from the supporting means into a pile to make a heel, means for ejecting the heel, and means arranged to engage the top of the pile for controlling the ejecting means.

79. A heel building machine having, in combination, means for supporting heel lifts, means for collecting the lifts from the supporting means into a pile to make a heel, means for ejecting the heel, and means arranged to engage the top of the pile for determining the time of operation of the ejecting means.

80. A heel building machine having, in combination, means for supporting heel lifts differing in certain of their characteristics, means for collecting the lifts in a predetermined order from the supporting means into a pile to make a heel, means for ejecting the heel, and a member arranged to engage the top of the pile for determining the time of operation of the ejecting means.

81. A heel building machine having, in combination, means for supporting heel lifts, means for collecting the lifts from the supporting means into a pile on a support to make a heel, means for ejecting the heel,

and a member arranged to be controlled by the growing pile to be positioned progressively at greater distances from the support for the heel and having connections for determining the time of operation of the ejecting means.

82. A heel building machine having, in combination, means for supporting a plurality of heel lifts, means for removing the lifts successively from the supporting means and assembling them in a pile to form a heel, and means movable upwardly as the pile increases in height for determining the height of the pile and thus of the thickness of the completed heel.

83. A heel building machine having, in combination, means for supporting a plurality of heel lifts, means for removing the lifts successively from the supporting means and assembling them in a pile, and a member movable upwardly with the growth of the pile for determining the final height thereof.

84. A heel building machine having, in combination, means for supporting a plurality of heel lifts, means for removing the lifts successively from the supporting means and assembling them in a pile, and a member movable upwardly with the growth of the pile for controlling the ejection of the pile when it has reached a predetermined height.

85. A heel building machine having, in combination, means for supporting heel lifts, means for removing the lifts successively from the supporting means and assembling them in a pile, means for applying paste between the lifts in the pile, and a member arranged to be moved upwardly with the growth of the pile and operative to interrupt the assembling operation when the pile has attained a predetermined height.

86. A heel building machine having, in combination, means for supporting heel lifts, means for removing lifts successively from the supporting means and assembling them in a pile, means for securing the lifts together for a heel, means for ejecting the heel thus formed, and a member movable upwardly with the growth of the pile for controlling said ejecting means.

87. A machine for handling heel-lifts having, in combination, lift holding means, lift receiving means, a conveying device movable between said two means and into alinement with one of them, and means co-operating with the conveying device for temporarily maintaining such alinement.

88. A machine for handling heel-lifts having, in combination, lift holding means, lift receiving means, a conveying device movable between said two means and into alinement with each of them, and means as-

sociated with both the holding and receiving means for temporarily maintaining the conveying device in alignment therewith.

89. A machine for handling heel-lifts having, in combination, lift holding means, lift receiving means, a device having a conveying movement between said means and an engaging and disengaging movement into and out of contact with the lifts, and means effective during the engaging and disengaging movement to prevent the conveying movement of the device.

90. A machine for handling lifts having, in combination, lift holding means, lift receiving means, a conveying device movable in one plane between said means and in another plane to engage and disengage lifts, and movement limiting means with which the conveying device co-operates to arrest said device after a prescribed travel.

91. A machine for handling heel-lifts having, in combination, lift holding means, lift receiving means, a device having a conveying movement between said means and an engaging and disengaging movement into and out of contact with the lifts, and means for limiting the extent of the conveying movement of the device and for preventing such movement during the engaging and disengaging movement.

92. A shoe machine having, in combination, a heel-lift conveyer movable between a magazine adapted to hold a stack of lifts and a lift-receiving station, means for arresting the movement of the conveyer upon arrival at said magazine or receiving station, and means for depressing the conveyer during said periods of rest and for co-operating with the conveyer to definitely and positively position it with relation to said

magazine or receiving station at the time of its depression.

93. A shoe machine having, in combination, a heel-lift conveyer movable between a magazine adapted to hold a stack of lifts and a lift-receiving station, means for arresting the movement of the conveyer upon arrival at said magazine or receiving station, means for depressing the conveyer during said periods of rest, and slotted guides co-operating with the conveyer to definitely position it with relation to said magazine or receiving station at the time of its depression.

94. A shoe machine having, in combination, a heel-lift conveyer movable between a magazine adapted to hold a stack of lifts and a lift-receiving station, means for arresting the movement of the conveyer upon arrival at said magazine or receiving station, means for depressing the conveyer during said periods of rest, a slotted member at each position of rest having a fixed vertical relation to the magazine or receiving station, and a member on the conveyer for engaging within said slot at the time of depression whereby to definitely position the conveyer with respect to the position at which its movement was arrested.

95. Mechanism for handling heel-lifts having, in combination, a conveying device angularly movable between lift-supplying and lift-receiving stations about a support intermediate said stations, and means co-operating with said device to periodically arrest its movement when at said two stations, alternately, and to center it with respect to the station at which it is brought to rest.
